UNITED STATES PATENT OFFICE.

WILLIAM D. HAMERSTADT, OF INDIANAPOLIS, INDIANA, ASSIGNOR TO ROCKWOOD MANUFACTURING COMPANY, OF INDIANAPOLIS, INDIANA, A CORPORATION.

PROCESS OF MAKING PULLEYS.

Application filed November 24, 1925. Serial No. 71,180.

This invention pertains to a paper or fibre pulley of the web type, that is, a pulley having a metal hub with a metal web radiating therefrom with a paper or fibre pulley shell 5 formed on transverse arms provided on the end of the web.

Heretofore such pulleys have been made by casting the hub and web in the usual manner with a plurality of transverse pins formed 10 or secured about the peripheral edge of the web upon which paper or fibre laminations are mounted and compressed, as shown in Letters Patent No. 1,923,165.

The object of this invention is to construct 15 a pulley of this type by forming a plurality of transverse bores through the fibre shell and die casting the hub and web with the transverse pins integral therewith formed in the bore provided in the shell. This has the 20 effect of not only reducing the cost of construction, but causing the transverse pins to be embedded, interlocked or bonded with the shell so as to firmly bind the metallic hub support and shell together as well as 25 secure the laminations in their compressed relation to each other as disclosed in Letters Patent No. 1,535,134.

Another feature of the invention resides in 30 simultaneously applying pressure to the metal and to the fibre shell during the die casting process, the pressure exerted on the shell being greater than that applied to the metal during the die casting, whereby the paper or fibre laminations will be tightly 35 compressed and the density thereof increased in which condition they will be permanently maintained by the bonding or interlocking effect of the die casting.

The full nature of the invention will be 40 understood from the accompanying drawings and the following description and claims.

Fig. 1 is a perspective view of a pulley structure of this type. Fig. 2 is an enlarged section taken on a line 2—2 of Fig. 1. Fig. 45 3 illustrates the arrangement of the fibre laminations before being subjected to the process. Fig. 4 is a section taken through the die employed with the fibre shell placed in position for receiving the metal casting.

50 In the drawings there is shown a pulley having a shell 10 formed of a plurality of fibrous rings or laminations such as paper or the like. Said rings are provided with a plurality of transverse bores 11 extending 55 from one side to the other or from adjacent

one side to a point adjacent the other side as may be desired, said bores are formed at intervals about the shell and are spaced substantially equi-distant between the inner and outer surfaces thereof. Intermediate the 60 sides of the shell and extending about the inner surface thereof there is formed an inwardly extending groove 12 communicating with the respective bores 11.

The supporting structure of the pulley 65 comprises the metallic hub 13 formed with a radiating web 14 which is formed integral in the manner hereinafter described, with the transverse pins 15' adapted to extend through the bores 11, said web 14 connecting said 70 pins through the recess or opening 12 formed in the shell.

The metallic structure is joined with the fibre shell by a die casting process. The process employed in constructing a pulley of this character consists in providing a pair of oppositely disposed die blocks 15 and 16 which may be mounted on the usual die casting machine. The dies are provided in their conformation with the annular shoulders 75 17 upon which a plurality of laminated rings as shown in Fig. 3 may be mounted or built up. The shoulders 17 will support them in proper position and alignment, or they may be temporarily clamped together by any 80 other suitable means. The die blocks 15 and 16 are thereupon brought together so as to clamp the rings forming the shell 10 together and compress them to about 20 or 25% of their natural width, increasing their density 85 accordingly. The die 15 is provided with the core 18 which is adapted to extend into a corresponding recess 19 formed in the block 16. The die 15 is also provided with a nozzle 90 20 formed therein which will conduct the molten metal to the hub forming chamber surrounding the core 18. The metal discharged therein under high pressure will be forced around the core 18 to form the hub 13 and into the space between the surfaces of the dies to form the web 14 and thence into the slot or recess 12 and the bores 11 to form the pins 15. A recess 21 may be formed about 95 the face of the dies into which the metal will flow to form the ribs 22 connecting the pins 15' for providing a suitable finish if desired, as shown in Figs. 1 and 2.

It will be noted herein that the pressure exerted by the dies against the laminations will be greater than the pressure exerted by 100 105 110

the metal, such pressures being created simultaneously. The metal forced under pressure into the bores 11 will penetrate the softer portions of the fibrous surface, and extend 5 into any irregularities thereof as well as bond itself with the fibres so as to create a bonding or interlocking effect with the laminations while held under high pressure. Consequently, upon the metal hardening and the 10 dies being removed, the density of the fibrous shell created by the pressure will be maintained by reason of the interlocking or bonding effect of the metal.

While as herein shown, the structure may 15 embody a solid web, the web may be spoke-like in structure if desired, without departing from the spirit of this invention. In this instance, the process of constructing the pulley would be the same, it necessitating 20 only an alteration in the shape of the die blocks. The spokes would be integral with the hub and transverse pins, each spoke extending radially from the hub to its respective pin.

25 The invention claimed is:

1. The process of forming a laminated paper pulley having a metallic hub and web for supporting the same, consisting in providing a pair of die members spaced apart 30 intermediate their peripheries to form a web therebetween, and to form an annular recess for receiving and clamping therebetween the laminated fibre rim, providing a core on one of said die blocks extending centrally 35 therefrom to the other die block and sur-

rounded with a recess to provide a hub portion, forming a plurality of transversely extending bores through said rim, forming a recess about the inner periphery of said rim in communication with said bores, suitably 40 clamping the same between said die blocks under such pressure as to reduce the width thereof and increase the density of the fibre, and die casting metal between said die blocks under sufficient pressure to force it into said bores through said recesses and into the intervening space between said blocks and the space surrounding said bore for forming transverse pins through said rim in bonded 45 relation with the fibrous surface thereof and forming a hub and web integral therewith.

2. The process of forming a laminated fibre pulley having a metallic hub and web portion, consisting in providing a pair of oppositely disposed die members, forming a plurality of transversely extending bores through said laminated fibre rim, providing a recess about the inner periphery of said rim in communication with each of said 50 bores, providing suitable openings in said die members for forming a web and hub portion, said openings communicating with said recess, and discharging metal therein under pressure for forcing it into said openings, recess and bores for causing said metal to bond with the fibre laminations and form 55 said hub and recess integral therewith.

In witness whereof, I have hereunto affixed my signature.

WILLIAM D. HAMERSTADT.
